UNITED STATES PATENT OFFICE.

EDWARD SWANSON, OF SHEFFIELD, ILLINOIS.

KNOCKDOWN HEN'S NEST.

1,315,432.

Specification of Letters Patent. Patented Sept. 9, 1919.

Application filed September 4, 1917. Serial No. 189,556.

To all whom it may concern:

Be it known that I, EDWARD SWANSON, citizen of the United States, residing at Sheffield, in the county of Bureau and State 5 of Illinois, have invented certain new and useful Improvements in Knockdown Hens' Nests; and I do hereby declare that the following is a full, clear, and exact description of the invention, such as will enable others 10 skilled in the art to which it appertains to make and use the same.

This invention has for its object to provide an improved hen's nest, and has for its particular object to provide a sheet metal 15 structure which may be knocked down for purposes of shipment, and which may be easily and quickly assembled and mounted on a wall, or the like.

A further object of the invention is to 20 provide a hen's nest which is so constructed as to prevent hens from roosting on the edges of the nest, for sanitary reasons.

The invention consists in the features of construction and combinations of parts hereinafter fully described and particularly 25 claimed.

In the accompanying drawings illustrating a suitable embodiment of the invention:

Figure —1— is a perspective view partly 30 broken away of a hen's nest constructed in accordance with the invention.

Fig. —2— is a fragmentary detail perspective sectional view of one of the front corner 35 portions of the nest on the line 2—2 of Fig. —1—.

Fig. —3— is a fragmentary detail plan section of one of the forward corner portions of the nest on the line 3—3 of Fig. —1—.

Fig. —4— is a fragmentary detail vertical section of one of the lower end corners of a nest on the line 4—4 of Fig. —1—.

Fig. —5— is a top plan view of a removable bracket or support adapted to be 45 movably mounted upon the forward end portion of the nest.

The nest consists of a rectangular receptacle of suitable dimensions comprising a bottom plate 1, side walls 2, a front wall 3, 50 and a rear wall 4. All of these parts are so constructed and arranged as to interfit and substantially interlock with each other in assembling the structure without requiring the use of tools or fastening devices of any kind except such as are integral with the 55 several parts.

At each side edge of the bottom plate 1 there is a substantially cylindrical flange or bead 5 projecting from the bottom thereof, and each of the side walls 2 is provided 60 along its bottom edge with a channeled flange 6 adapted to receive the bead 5. The said bead 6 presents an open channel having a mouth portion into which the bead 5 is received, instead of being longitudinally 65 inserted if desired. The front and rear edges of the bottom plate 1 are plain, and are received in the channeled recesses 7 at the lower ends of the front wall 3 and rear wall 4, said lower edge portions of said last- 70 named walls being substantially N-shaped to provide the channel 7 in an obvious manner. The side walls 2 are further provided along their front and rear edges with vertical flanges 8, and the front and rear walls 75 3 and 4 are also provided along their side edges with vertical flanges 9. The said flanges 9 are adapted to abut against the inner faces of the side walls 2 and the flanges 8 of the latter are adapted to abut 80 against the outer faces of the front and rear walls. At the upper end of each of the flanges 8 is an integral tongue 10 extending normally to a higher elevation than the corresponding edge portions of said side walls 85 3 and 4, and higher than the front and rear walls, and are bent over the upper edges of the latter when the structure is assembled for 90 permanently locking the several parts in the proper relative positions. The said 90 tongues 10 are so disposed that the outer side edges of the same, when bent over, abut against the inner faces of the flanges 9 of the front and rear walls 3 and 4. In this manner the upper end portions of the side 95 walls 2 are prevented from swinging outwardly and the front and rear walls are prevented from swinging inwardly, as will be apparent.

The upper edges of the side walls 2 are inclined from a point contiguous to the upper rear corners of the same to their forward edges, and said inclined portions are provided with narrow flanges 11 extending about one-half the length of the edge from the upper end portions to about the middle portion. The flanges 11 are folded over upon the outer faces of the side walls 2, and the flanges 12 extending from the inner ends of the flanges 11 to the forward ends of said side walls are folded over upon the inner side faces thereof. The flanges 11 are offset 100 105 110

slightly from the outer faces of the walls 2 so as to provide channeled guides adapted to receive the channeled flanges 13 of a cover member 14 which is of a width substantially 5 equal to the distance from the forward end of the flanges 11 to the rear wall of the receptacle. The cover member consists of a flat plate having a rear edge flange 15 which is adapted to abut against the rear face of the rear wall 4, the forward edge of said cover being V-shaped, as shown at 16, to provide an enlarged opening midway between the side walls of the nest to render it convenient for the hen to enter the latter. The 10 front wall 3 is similarly provided with a V-shaped recess 17 extending from the side edge portions thereof to the middle portion of the same, and the edges of said recess are provided with narrow flanges which are folded over upon the inner face of the front wall so as to provide rounded edges for the recess which are adapted to prevent any injury to the hen's feet in the event that she should attempt to roost on said edges. The 15 edges of the recess 16 in the cover 14 are similarly rounded to prevent any injury to the hen.

In the rear wall are two openings 18 contiguous to the upper corners of the same to 30 receive the heads of nails, screws or hooks mounted in the wall or other support from which the nest is to be suspended.

It will be noted that the beads 5 are hollow, and are adapted to telescopically receive the rods 19 projecting from the rear edge of a substantially triangular shelf 20 adapted to be mounted to project from the lower front corner of the nest, as shown in Fig. —1—, and which may constitute a temporary approach for the hen in entering and leaving the nest. The rods 19 are integral with each other, and constitute continuations of a border wire over which the front edge and inclined side edges of the shelf or 40 approach 20 are bent for securing the said rod in place, and at the same time forming rounded exposed corners or edges for the same. The rear edge of the shelf 20 is received in the outer recess or groove 21 45 formed in the aforesaid N-shaped lower end or edge of the front wall 3 of the nest.

In assembling the nest the end walls and bottom member are first connected together by engaging the ends of the bottom member 50 in the recesses 7 of the end walls. The side walls are then mounted on the bottom member by engaging the beads 5 in the channeled flanges 6. The tongues 10 are then bent over, as shown in Fig. —2—, whereupon a very 60 strong substantially rectangular receptacle is formed which cannot possibly be distorted or knocked down without applying sufficient force to distort the metal, or by turning up said tongues 10. The structure is further 65 reinforced by mounting the cover 14 thereon

as this prevents any indentation or distortion of the side walls 2 by lateral pressures. The shelf or approach 20 is then mounted in position, whereupon the nest is complete and ready for use.

Before mounting the cover 14 on the nest the same is held against the supporting surface from which it is to be suspended, and the position of the supporting nails, screws or hooks marked through the openings 18. 70 Then after the said supports have been mounted in position the cover 14 is placed on the receptacle and the latter is hung.

While I have shown the preferred embodiment of the invention in the accompanying drawings, it will be obvious, of course, that the construction may be changed and varied in details without departing from the invention as defined in the appended claims.

I claim as my invention:

1. A hen's nest comprising a receptacle open at the top and adapted to be mounted on a wall, said receptacle having a front wall and side walls, the upper edges of all of said walls presenting smooth inclined edges 90 adapted to prevent roosting thereon.

2. A hen's nest comprising a rectangular receptacle open at the top having side walls presenting upper inclined smooth edges, and a front wall presenting two relatively angularly disposed inclined smooth edges, all adapted to prevent roosting of hens on the edges of the nest.

3. A hen's nest comprising a rectangular receptacle adapted to be shipped in knock-down condition for assemblage by the recipient, and consisting of a bottom plate and side walls having inter-engaging edge formations, end walls each provided with edge formations adapted to receive the front and rear edges of the bottom plate, said end and side walls each provided with right angled flanges along their vertical edges, the flanges of the side walls abutting against the outer faces of the end walls and said flanges of the latter abutting against the inner faces of the side walls, the flanges of the latter terminating at their upper ends in tongues bent over upon the upper edges of the end walls inwardly of and in engagement with the flanges thereof, whereby a relative lateral movement of the side and end walls is prevented, the latter supported by the end edge portions of the bottom wall.

4. A hen's nest comprising a rectangular receptacle adapted to be shipped in knock-down condition for assemblage by the recipient, and consisting of a bottom plate and two opposed vertical walls having inter-engaging edge formations, the remaining vertical walls provided with grooves adapted to receive the edges of said bottom for preventing vertical movement of said walls with respect to said bottom, the several pairs of walls being equipped along their vertical 125 130

- edges with right angled flanges, those of the first - named walls overhanging the outer faces of the last-named walls for preventing outward movement thereof and preventing movement of the bottom relatively to the first-named walls, the flanges of the last-named walls abutting against the inner faces of the first-named and the flanges of the latter terminating in tongues folded over upon the upper edges of the last - named walls and engaging the inner faces of the flanges thereof, whereby said vertical walls are rigidly held in proper relative positions.
5. A hen's nest comprising a receptacle consisting of a bottom wall, two side walls, a front wall, a rear wall, and a cover, the upper edges of the side walls inclined from the rear ends to the front ends thereof, and the upper edge of the front wall presenting 10 a V-shaped recess extending from the side edges to the middle thereof, said cover engaged with the upper edges of the side walls and extending at an incline from the rear wall to a point about midway between the front and rear walls.
- 15 6. A hen's nest comprising a receptacle consisting of a bottom wall, two side walls, a front wall, a rear wall, and a cover, the upper edges of the side walls inclined from the rear ends to the front ends thereof, and the upper edge of the front wall presenting 20 a V-shaped recess extending from the side edges to the middle thereof, said cover engaged with the upper edges of the side walls and extending at an incline from the rear wall to a point about midway between the front and rear walls.
- 25 7. A hen's nest comprising a receptacle consisting of a bottom wall, two side walls, a front wall, a rear wall, and a cover, the upper edges of the side walls inclined from the rear ends to the front ends thereof, and the upper edge of the front wall presenting 30 a V-shaped recess extending from the side edges to the middle thereof, said cover engaged with the upper edges of the side walls and extending at an incline from the rear wall to a point about midway between the front and rear walls, the front edge of the cover having a V-shaped recess therein extending from the side edges to the middle thereof.
- 35 40 8. A hen's nest comprising a receptacle consisting of a bottom wall, two side walls, a front wall, a rear wall, and a cover, the upper edges of the side walls inclined from the rear ends to the front ends thereof, the upper edges of the side walls equipped with outwardly overturned flanges extending from the rear ends to about midway between the ends thereof, and equipped with inwardly overturned flanges extending from about midway between the ends thereof to the front ends of the same, the said cover engaged with said outwardly overturned flanges and terminating at the inner ends 45 of the inwardly overturned flanges of said 50 side walls.
